UNITED STATES PATENT OFFICE.

MABEL C. BARBER, OF CHICAGO, ILLINOIS.

MATTRESS RETAINER.

Application filed December 31, 1925. Serial No. 78,516.

The present invention relates to a device for retaining a mattress in position relative to the bed, and among the objects of my invention is to provide a novel mattress retainer of the type specified.

A further object is to afford a mattress retainer having means to hold the device in place, and in a more specific sense to hold the mattress against slipping when the portions supporting the mattress are moved out of the normal horizontal position.

Another object is to create a mattress retainer which is of simple construction and adjustability and is easily applied and removed from a mattress.

A still further object is to afford a device which will hold the mattress and clothing in position in a positive manner and which will not injure same and will present a slightly appearance when in position on a bed.

A further object is to provide a clamping means for holding a mattress which is inclined as on a hospital bed or is vertical as in an in-a-door bed put up for the day, from slipping down from held position, and such further objects, advantages and capabilities as will later more fully appear.

My invention further resides in the combination, construction and arrangement of parts illustrated in the accompanying drawings, and while I have shown therein preferred embodiments of my invention, I wish it understood that the same is susceptible of modification and change without departing from the spirit of my invention.

Referring to the drawings, Fig. 1 is a perspective view of a hospital bed showing a mattress in inclined position with the mattress and a portion of the springs and frame partly broken away to show my mattress retainer in clamping position.

Fig. 2 is a perspective view of an in-a-door bed in vertical position with the mattress and spring frame partly broken away to show my new clamping means in use.

Fig. 3 is a sectional vertical view of my mattress retainer as applied to a mattress.

Fig. 4 is a cross-section on line 4-4 of Fig. 3.

Fig. 5 is a plan view.

Fig. 6 is a perspective view showing the lower plate and hook in detail and also the upper plate member about to be joined to the lower plate.

Fig. 7 is a vertical view partly in section

of a slightly different embodiment of my invention showing the hook disposed nearer the free end of the clamping jaw.

My invention more in detail comprises a pair of spaced jaws 1 and 2, said jaws becoming wider toward the bottom as shown at 3, and bending inwardly to form a grip 4. At the top both jaw members 1 and 2 are bent at right angles as shown at 5 and the material of jaw 1 is continued to form lower plate 6 and jaw 2 to form upper plate 7. The lower plate 6 has flanged edges 8 to hold the upper plate in slidable relation therebetween. A hook 9 is stamped out of jaw 1 and extends outwardly from the under surface of plate 6 as clearly shown in Fig. 6. This hook 9 may also be stamped out the reverse of the embodiment shown in Fig. 6 so that it will extend from the opposite end of the opening as clearly shown in Fig. 7, if desired, in order to accommodate a longer mattress. The upper plate 7 has a slot 11 which slides over a screw threaded hole 10 in lower plate 6. When the point of adjustment is found between the plates so that the jaws tightly grip the mattress to be held, a wing bolt 12 which passes through slot 11 and into threaded engagement with hole 10 is tightened to hold

the device in fixed position with relation to the mattress. In Fig. 1 my device is shown in use on a hospital bed where an inclined spring and mattress are used.

When holding a mattress of approximately the proper length the hook 9 (of Figs. 1 and 6) is placed over the upper side of the end member of the bed frame as shown in Figs. 1 and 3. When my device is applied to a mattress of such length as to

protrude a substantial distance beyond the end member of the bed frame, the form shown in Fig. 7 is availed of and the hook being nearer the free end of the jaw 1 will, when placed over the end member of the bed frame accommodate the extra length of the mattress without causing buckling of the latter.

When applied in hospital bed service as shown in Fig. 1, the mattress is positively held against slipping downwardly under continued bodily movement of the patient or action of gravity thus eliminating the constant source of annoyance to nurses heretofore occasioned by the repeated necessity of having to pull the mattress upwardly to its elevated and smooth con-

dition for which latter work nurses are usually forced to call for assistance.

When my device is used for holding in-a-door bed mattresses in vertical position as shown in Fig. 2, the mattress is securely held in positive position without danger of the mattress and bed clothing being found in disarranged condition when the bed is lowered at night for use.

10 This device is easily and quickly applied, readily adjustable to different thicknesses of material to be gripped, and is positive in its operation.

While I have illustrated only two uses 15 of my improved device, it is, of course, obvious that it may be applied to other uses without departing from the spirit of my invention.

Having now described my invention, I 20 claim:

1. A mattress retainer comprising a pair of clamping jaws each having a portion bent as substantially a right angle to the main jaw portion to form adjusting plates 25 slidable one upon the other, one of said plates having means to hold the other longitudinally slidable thereon, means to fasten said plates against sliding movement when the jaws have been properly adjusted, 30 one of said plates having an extension thereon, the end of said extension being formed into a hook positioned laterally outside of the two jaws, said hook being formed integrally with the nearest jaw, so that when 35 a mattress is secured between said jaws the hook may be hooked over an adjacent portion of the bed frame to hold the mattress against substantial displacement when moved out of horizontal position.

40 2. A mattress retainer comprising a pair of jaws each having an angularly bent portion to form adjusting plates slidable one upon the other, means carried by one of said plates and cooperating with the other plate 45 to fasten them against slidable movement when the jaws have been adjusted with the mattress tightly held between, a hook integral with and extending downwardly from the lower jaw when the jaws are in horizontal position, so that when the jaws have 50 a mattress clamped therebetween the hook may be hooked over an adjacent portion of the bed frame normally beneath the mattress, to prevent substantial displacement of 55 the mattress when moved out of horizontal position.

3. A mattress retainer comprising a pair of clamping jaws each formed with an an-

gularly extending portion, said portions being slidable one on the other, tightening 60 means extending through the angularly extending portions to lock them against sliding when the jaws have been adjusted to grip a mattress therebetween, and a hook on one of said jaws to hook over an adjacent 65 portion of a bed frame to hold the mattress against substantial displacement when the adjacent portion of the bed frame has been moved out of horizontal position.

4. In a mattress retainer for holding a 70 mattress against substantial displacement with relation to a bed frame when moved out of horizontal position, a pair of jaws each having an angularly extending portion, 75 said portions being slidable one on the other, tightening means carried by one of said angularly extending portions and cooperating with the other of said portions to lock them against sliding movement relatively to each other when the jaws are adjusted to grip 80 a mattress, and a hook on one of said jaws extending downwardly when the jaws are in horizontal position, said hook being adapted to take over an adjacent portion of a bed frame to hold the mattress against 85 slipping when the adjacent portion of the bed frame and the mattress are moved to a vertical or inclined position.

5. In a mattress retainer a pair of jaws having opposing faces each having an angularly extending portion slidable one on the other, releasable locking means to lock 90 said portions against sliding movement when a mattress is gripped between the jaws, and a hook extending laterally from one of said 95 opposing faces, said hook being adapted to take over an adjacent portion of a bed frame to hold the mattress against displacement when moved out of horizontal position.

6. A mattress retainer having a pair of 100 jaws, a plate at one end of each of said jaws and at right angles thereof, one of said plates having a flange and a hole, the other of said plates having a slot, said plates being held in slidable engagement with each 105 other by said flange, and slidable to determine the adjustment of said jaws, means projecting through the hole in the flanged plate and the slot in the other plate to hold the plates in adjusted position, and a hook 110 stamped from the material of one of the jaws to engage over a cooperating support for the mattress.

In witness whereof, I hereunto subscribe my name to this specification.

MABEL C. BARBER.
